United States Patent Office

Des. 185,410
Patented June 9, 1959

185,410

FLUORESCENT LIGHT FIXTURE

Marcus Bodian, Los Angeles, and William B. Rosenfield, Pacoima, Calif., assignors to Sunbeam Lighting Company, Los Angeles, Calif., a firm

Application January 22, 1957, Serial No. 44,542

Term of patent 14 years

(Cl. D48—23)

Fig. 1 is a perspective view of a fluorescent light fixture showing our new design on a reduced scale;

Fig. 2 is a bottom plan view;

Fig. 3 is a top plan view;

Fig. 4 is a side elevational view;

Fig. 5 is a side elevational view with parts broken away to show configurational details of the design;

Fig. 6 is an end elevational view; and

Fig. 7 is an end elevational view with parts broken away to show configurational details of the design.

We claim:

The ornamental design for a fluorescent light fixture, as shown.
